CLAIM

The ornamental design for a headgear for physical therapy, as shown and described.

DESCRIPTION

FIG. 1 is a front elevational view of headgear for physical therapy showing my new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a front elevation view of the headgear for physical therapy, shown in condition of use for clarity of disclosure; and,

FIG. 8 is a right-side elevation view thereof.

The equal-length broken lines in the photographs depict environmental structure of the headgear for physical therapy that form no part of the claimed design.

1 Claim, 8 Drawing Sheets
